UNITED STATES PATENT OFFICE.

WILLIAM S. AULT, OF WABASH, INDIANA; MARY AULT EXECUTRIX OF SAID WILLIAM S. AULT, DECEASED.

HINGE.

1,128,931.

Specification of Letters Patent. Patented Feb. 16, 1915.

Application filed July 22, 1913. Serial No. 780,486.

To all whom it may concern:

Be it known that I, WILLIAM S. AULT, a citizen of the United States, residing at Wabash, in the county of Wabash and State of Indiana, have invented new and useful Improvements in Hinges, of which the following is a specification:

The invention relates to hinges and more particularly to those adapted for use in connection with door frames to which are adapted to be connected or attached, any well known form of fly screen, and the object of the invention is to provide a simple and novel means whereby the hinge proper can be conveniently and readily attached to or removed from the frame of the screen.

The invention embodies, among other features, various improvements over my Patent No. 972,090 granted October 4, 1910.

In the further disclosure of the invention reference is to be had to the accompanying drawings, constituting a part of this specification, in which similar characters of reference denote corresponding parts in all the views, and in which:

Figure 1 is a front elevation of the hinge showing the same in applied position; Fig. 2 is a rear elevation of the hinge; Fig. 3 is a front elevation of the hinge, showing the hinge proper disconnected from the bracket; Fig. 4 is a horizontal sectional view taken on the line 4-4 in Fig. 1; and Fig. 5 is a fragmentary vertical sectional view taken on the line 5-5 in Fig. 1. Fig. 6 is a fragmentary side elevation of the bracket.

Referring more particularly to the views. I provide a hinge 10 including a plurality of connected leaves 11, 12, and a bracket 13, the leaf 11 being connected by suitable screws to a door 14 and the said bracket connected by suitable screws to a door casing 15. Lateral ears 16 are struck from the leaf 11 and provided with apertures 17 and similarly, lateral ears 18 are struck from the leaf 12 and provided with apertures 19, the said leaves 11 and 12, when connected, being adapted to have the apertures 17 and 19 of the respective ears 16 and 18 register in order that a pintle 20 can be passed therethrough to pivotally connect the leaves, a helical spring 21 being arranged between the upper and lower ears 18 of the leaf 11 and encircling the pintle 20, with one end 22 of the spring abutting against the face of the leaf 11 and the other end 23 of

the spring abutting against the face of the leaf 12, it being readily understood that the spring is provided for the purpose of exerting opposing pressure against the leaves 11 and 12, a suitable circular casing 24 being arranged to encircle the spring 21, as shown.

In order that the leaves 11 and 12 will normally lie in the same vertical plane so that the hinge proper can be applied to the flat face of the door 14, a lateral rib 25 is struck rearwardly from the leaf 12 and is adapted to be engaged by an edge of the leaf 11 so as to limit the rearward swinging movement of the leaf 11 with respect to the leaf 12 when acted upon by the spring 21, as will be readily apparent.

An integral tongue 26 is struck from the leaf 12 and is provided with an open slot 27 terminating at its inner end in a circular aperture 28.

As mentioned heretofore, the bracket 13 is carried on the door casing 15. The bracket 13 is preferably formed of a single piece of stamped material and is provided with upwardly struck lugs 29 adapted to be engaged by an edge of the leaf 12 for securing the leaf in engagement with the bracket, similar lugs 30 being also struck upwardly from the face of the bracket 13 and adapted to be engaged by the tongue 26 to hold the tongue securely against the face of the bracket, these lugs 29 and 30 also acting as guide members when the hinge proper is engaged with the bracket.

Now in order to secure a rigid structure when the hinge proper is connected with the bracket as mentioned, I provide a plurality of integral flanges 31 projecting beyond the inner edge of the bracket 13 and adapted to pass through transverse slots 32 formed in the rearwardly extending rib 25 of the leaf 12. It will therefore be apparent by referring to Fig. 2 that when the hinge proper is connected with the bracket 13, the flanges 31 will pass through the slots 32 to secure the inner end of the bracket to the hinge proper, while the lugs 29 and 30 will be engaged by the leaf 12 and tongue 26 thereof so that the hinge proper, when connected with the bracket, will operate as a rigid structure. In order to lock the hinge proper on the bracket 13 a revoluble key 33 is supported on the bracket 13 and when the leaf 12 of the hinge proper engages the bracket the shank 34 of the key will be received in the ap-

erture 28 formed at the inner end of the slot 27, the said shank having been previously passed through the slot 27 so that the turning of the key 33 in the aperture 28 will lock the leaf 12 to the bracket, the width of the shank 34 being greater than the width of the slot 27 and which width is presented toward the slot when the key is in locked position, whereas when the key is turned into an un-

locked position, the edge of the shank will be presented to slot and in consequence of the edge of the slot being wider than the edge of the shank, the said shank will readily pass through the slot when the hinge proper is disengaged from the bracket.

Now from the foregoing description and from the views it will be apparent that the hinge proper can be secured in a rigid position with respect to the bracket, that is, the leaf 12 of the hinge proper will be rigid relatively to the bracket and which is secured to the door casing, whereas the leaf 11 is secured to the door 14 so that the device, to all appearances, will appear as an ordinary hinge. Now when it is desired to remove the door from the door casing it is only necessary to turn the key 33 into an unlocked position and then by pulling outwardly on the door the leaf 12 will be disengaged from the bracket 13, thus entirely removing the door together with the hinge proper, from the door casing and the bracket carried thereby.

As mentioned heretofore, the device disclosed herein embodies various improvements over the construction disclosed in my

former patent and although I preferably form various parts of the present invention by stamping the same from material in blank, it will be understood that various changes can be made in the construction disclosed herein without departing from the spirit of the invention.

Having thus described my invention, I claim:

1. A hinge comprising pivotally connected leaves, one of the said leaves having a slot therein which extends to one side edge of the leaf, a bracket for detachable engagement with the slotted leaf of the hinge, a locking element movably mounted on the bracket for locking engagement in the said slot, a rib projecting from the first mentioned leaf, and flanges projecting from the bracket and adapted to pass through apertures in the said rib.

2. A hinge comprising pivotally connected leaves, a bracket for locking engagement with one of the leaves, a longitudinal rib struck from the said leaf and adapted to be engaged by and form a stop member for the other leaf, and flanges projecting from the bracket and adapted to pass through apertures in the said rib to support the first mentioned leaf on the bracket.

In testimony whereof I affix my signature in presence of two witnesses.

WILLIAM S. AULT.
